CAP.

No. 19,354.

Patented Oct. 15, 1889.

UNITED STATES PATENT OFFICE.

JACOB M. FRANK, OF PHILADELPHIA, PENNSYLVANIA.

DESIGN FOR A CAP.

SPECIFICATION forming part of Design No. 19,854, dated October 15, 1889.

Application filed February 16, 1889. Serial No. 300,173. Term of patent 3½ years.

To all whom it may concern:

Be it known that I, JACOB M. FRANK, a citizen of the United States, residing in the city and county of Philadelphia, State of Pennsylvania, have invented and produced 5 a new and original Design for Caps, of which the following is a specification, reference being had to the accompanying photograph, forming part thereof.

10 The leading feature of my design for a cap is a body portion having an ornamentation in front and bottom, consisting of a rounded rim, a rounded collar continuous thereof, and a frill within said rim.

In the drawing, A designates the body portion of the cap.

B designates a rounded rim; C, a frill within the same, and D a rounded collar continuous of the rim.

Having thus described my invention, what 20 I claim as new, and desire to secure by Letters Patent, is—

The design for the shape and ornamentation of a cap, as shown and described.

JACOB M. FRANK.
